ABSTRACT

A machine for loading a stack of articles in a carton which includes a carton erecting station and a carton loading station. A carton erecting plow device at the carton erecting station engages a flap of the carton and restrains and raises that flap to erect the carton at the carton erecting station as the carton is advanced. The carton is further advanced from the erecting station to the loading station. At the loading station is a pivotally mounted stack turning frame. A stack of articles in upright position is advanced into the stack turning frame. A stack advancing head carried on the stack turning frame engages the stack and holds the stack against stack holding flap means while the stack turning frame is swung to a position in which the stack is horizontal and opposite the carton. The flaps are released and the head is advanced further to advance the stack into the carton. A stack supporting tongue holds the articles up as the stack is advanced. When the stack has been advanced into the carton, the flaps of the carton are glued shut and the loaded carton is discharged.

FIG. 60

**MACHINE FOR LOADING A STACK OF ARTICLES
IN A CARTON**

This invention relates to a machine for erecting and loading cartons.

An object of this invention is to provide a machine which automatically withdraws a flat carton from a group of cartons and erects the carton.

A further object of this invention is to provide such a machine which, when required, advances the erect carton to a loading station and advances a stack of articles into the carton.

A further object of this invention is to provide such a machine in which the stack is advanced horizontally into the erect carton and in which means is provided for holding the articles in the stack upright as the stack is advanced into the carton.

A further object of this invention is to provide such a machine which closes flaps of the carton when the stack has been advanced into the carton and glues the flaps shut.

Briefly, this invention provides a machine to which cartons are supplied in a group or row. Suction cups draw a leading carton from one end of the row into position to be advanced upwardly by moving flights into a tilt table. The tilt table is swung to a carton release position and the carton drops to an erecting station. At the erecting station, plow members swing downwardly and turn major flaps of the carton down so that the plow members can engage trailing minor flaps of the carton. Then, a conveyor advances the carton, and the plow members swing upwardly while holding the trailing minor flaps to erect the carton. The erect carton is advanced to a loading station at which front minor flaps of the carton are closed. The edges of the minor flaps are spaced, and a stack supporting tongue is extended through the space between edges of the front minor flaps to extend lengthwise of the carton for supporting the stack of articles as the stack is advanced into the carton. The stack is advanced into the carton by a stack inserting assembly which receives the stack in upright position. The stack is pressed upwardly by a head of the stack inserting assembly to engage stack holding flap members. The flap holding members and the head are swung to bring the stack into alignment with the carton, and the head is advanced as the flap members are released to push the stack into the carton. When the stack has been pushed into the carton, rear minor flaps are closed by swinging upstream and downstream flap closing heads. The stack inserting head is withdrawn. Then, the downstream flap closing head is advanced to adjacent the upstream flap closing head. The carton is advanced through gluing assemblies where glue is applied to major flaps of the carton while the minor flaps are held in closed position and through major flap closing assemblies which close the major flaps. Then the carton is advanced into a compression section where the flaps are held in closed position while glue sets.

The above and other features and objects of the invention will be apparent to those skilled in the art to which this invention pertains from the following detailed description and the drawings, in which:

FIG. 1 is a somewhat schematic view in side elevation of a carton erecting and loading machine constructed in accordance with an embodiment of this invention, some details being omitted for clarity;

FIG. 2 is a view in side elevation on an enlarged scale of a carton pick-up section of the machine, a fragmentary portion of a carton feeding conveyor being shown schematically in association therewith;

5 FIG. 3 is a view looking in the direction of the arrows 3-3 in FIG. 2, conveyor chains being partly broken away to reveal structural details;

10 FIG. 4 is a fragmentary view looking in the direction of the arrows 4-4 in FIG. 3 showing drive chain connections;

FIG. 5 is a view in section taken on an enlarged scale on the line 5-5 in FIG. 3;

FIG. 13 is a perspective view of a carton which is erected and loaded in the machine;

35 FIG. 14 is a fragmentary plan view of the carton erecting and a carton loading section of the machine, some portions being omitted for clarity, an upstream flap closing assembly being shown in retracted position;

40 FIG. 15 is a fragmentary view in section taken on the line 15-15 in FIG. 14 showing a first flap closing assembly of the machine, other portions being omitted for clarity;

FIG. 16 is a view in section taken on the line 16-16 in FIG. 15;

45 FIG. 17 is a fragmentary view in front elevation showing a front flap closing assembly of the machine;

50 FIG. 18 is a view in section taken on the line 18-18 in FIG. 17, a lever member of the front flap closing assembly being shown in retracted position in dot-dash lines and in advanced position in full lines;

FIG. 19 is a fragmentary plan view partly in horizontal section showing the carton loading station of the machine and associated assemblies;

55 FIG. 20 is a fragmentary view in section taken on the line 20-20 in FIG. 19;

FIG. 21 is a view in section taken on the line 21-21 in FIG. 20;

FIG. 22 is a fragmentary view in front elevation showing a stack supporting assembly of the machine;

60 FIG. 23 is a view in section taken on the line 23-23 in FIG. 22;

FIG. 24 is a view in section taken on the line 24-24 in FIG. 22;

65 FIG. 25 is a fragmentary plan view on an enlarged scale of a wheel of the stack supporting assembly showing a portion of a tongue associated therewith;

FIG. 26 is a view in section taken on the line 25-25 in FIG. 25;

FIG. 27 is a fragmentary view in rear elevation showing an upstream flap closing assembly of the machine, a limit switch being omitted for clarity;

FIG. 28 is a view in section taken on the line 28—28 in FIG. 27;

FIG. 29 is a view in section taken on the line 29—29 in FIG. 28, a head thereof being shown in closed position in dot-dash lines, a fragmentary portion of a carton being shown in section in association therewith;

FIG. 30 is a fragmentary view in end elevation of the upstream flap closing assembly showing a limit switch associated therewith;

FIG. 31 is a plan view of a downstream flap closing head and associated members of the machine, the head being shown in open position in full lines and in closed position in dot-dash lines;

FIG. 32 is a view in section taken on the line 32—32 in FIG. 19;

FIG. 33 is a view taken in the direction of the arrows 33—33 in FIG. 19, some parts being broken away or omitted to reveal structural details and for clarity;

FIG. 34 is a view in section taken on the line 34—34 in FIG. 33, a stack inserting linkage being shown in extended position;

FIG. 35 is a view taken in the same direction as FIG. 34 but showing the stack inserting linkage in retracted position, a stack advancing assembly of the machine being shown in tilted position in dot-dash lines;

FIG. 36 is a fragmentary view in section taken on the line 36—36 in FIG. 34;

FIG. 37 is a view in section taken on an enlarged scale on the line 37—37 in FIG. 34;

FIG. 37A is a view in section taken on the line 37A—37A in FIG. 33;

FIG. 38 is a fragmentary view in section taken on an enlarged scale on the line 38—38 in FIG. 33;

FIG. 39 is a fragmentary view in front elevation of a bar guide assembly of the machine;

FIG. 40 is a view in section taken on the line 40—40 in FIG. 39;

FIG. 41 is a view looking in the direction of the arrows 41—41 in FIG. 40, a frame member being shown in dot-dash lines;

FIG. 42 is a view in section taken on an enlarged scale on the line 42—42 in FIG. 40;

FIG. 43 is a fragmentary view in front elevation of a glue assembly of the machine;

FIG. 44 is a view in section taken on the line 44—44 in FIG. 43;

FIG. 45 is a view looking in the direction of the arrows 45—45 in FIG. 44, glue heads and valves being omitted;

FIG. 46 is an enlarged view in section taken in the direction of the arrows 46—46 in FIG. 43;

FIG. 47 is a view in section taken on the line 47—47 in FIG. 46;

FIG. 48 is a fragmentary view in front elevation of a cantilever guide member of the machine;

FIG. 49 is a view in section taken on the line 49—49 in FIG. 48, a clamp being omitted for clarity;

FIG. 50 is a view in the direction of the arrows 50—50 in FIG. 49;

FIG. 51 is a fragmentary view in front elevation showing a final flap closing assembly of the machine;

FIG. 52 is a view in section taken on the line 52—52 in FIG. 51;

FIG. 53 is a view in section taken on an enlarged scale on the line 53—53 in FIG. 1 showing a vertical compression section of the machine;

FIG. 54 is a view taken in the direction of the arrows 54—54 in FIG. 53;

FIG. 55 is an enlarged fragmentary view in end elevation of a roller assembly of the vertical compression section;

FIG. 56 is a schematic view showing a portion of electrical connections of the machine;

FIG. 57 is a schematic view showing a further portion of the electrical connections of the machine;

FIG. 58 is a schematic view showing hydraulic connections of the machine;

FIG. 59 is a schematic view showing a portion of pneumatic connections of the machine;

FIG. 60 is a schematic view showing a further portion of pneumatic connections of the machine; and

FIG. 61 is a schematic view showing vacuum connections of the machine.

In the following detailed description and the drawings, like reference characters indicate like parts.

In FIG. 1 is shown a machine 40 constructed in accordance with an embodiment of this invention. The machine includes a carton pick-up section 42, a carton erecting and loading section 43, and a vertical compression section 44.

CARTON PICK-UP SECTION

Flat cartons 71 enter the machine in upright position on a conveyor 72, part of which is shown in FIG. 2. A stack of cartons is supported on the conveyor 72. The carton pick-up section 42 receives the cartons from the conveyor 72. The section 42 includes a stationary sloping frame 75. The cartons advance from the conveyor 72 onto lower guide bars 76 and 77 (FIG. 3) and the leading carton stops at rolls 78 and 79 carried by the guide bars 76 and 77 and on a roll 83 (FIG. 5). When a carton is called for by the machine, vacuum cups 84 and 86 (FIG. 3) advance from the position at which the vacuum cup 86 is shown in full lines in FIG. 5 to the dot-dash line position indicated at 86A at which the vacuum cups engage the leading carton 71A. The vacuum cups 84 and 86 are carried by similar mount structures, and only the mount structure for the vacuum cup 86 will be described in detail. The vacuum cup 86 is carried by a support block 87 which, in turn, is supported on a piston rod 88. The piston rod 88 also carries a piston 89 (FIG. 60) which works in a cylinder 91. The cylinder 91 (FIG. 5) is mounted on a generally angle-shaped mounting bracket 92, which swings on a pivot pin 93 supported by a stationary bracket 94 attached to a cross frame 96 of the carton pick-up assembly frame 75. A compression spring 97 urges the cylinder 91 and the swinging bracket 92 to the FIG. 5 position. A stop bolt 98 limits swinging of the bracket 92 in a counterclockwise direction. A vacuum can be impressed on the interior of the vacuum cup 84 through a channel 99 in the support block 87. When the vacuum cups have been advanced to the dot-dash line position 86A and into engagement with the leading carton 71A, a vacuum is impressed on the vacuum cups and the cups are drawn to the full line position of FIG. 5 to draw the leading carton against carton guides 102 and 103 (FIG. 3).

The carton is advanced from the vacuum cups by flights 104 and 106 carried by conveyor chains 107 and

108 which run on sprockets 109, 110, 111, and 112, and are supported by chain guides 113 and 114. The sprockets 109 and 110 are carried by a shaft 115, and the sprockets 111 and 112 are carried by a shaft 116. The shafts 115 and 116 are rotatably mounted in appropriate bearings 117 mounted on the frame 75 of the carton pick-up section 42. The shaft 116 is driven by a chain 1171 (FIGS. 2 and 3) which runs on a sprocket 118 (FIG. 3). The chain 117 also runs on a sprocket 119 (FIG. 2) which is driven by a motor 120 carried by a main stationary frame of the machine. The motor 120 drives gearing (not shown) in a gear box 121 (FIG. 2) which drives a suitable brake-clutch unit (not shown in detail) which drives the sprocket 119. A limit switch 1201 (FIGS. 3 and 5) provided with an actuator 1202 is actuated when the flights are in a position to pick up the carton. A limit switch 1203 provided with an actuator 1204 is actuated by the flight 104 when the flights 104 and 106 are in a home positon.

The flights 104 and 106 advance the leading carton under a discriminator blade 1211 which prevents feeding of more than a single carton at one time. As shown in FIG. 6, the discriminator blade 1211 is mounted on a cross bar 122, which includes threaded end blocks 123 and 124. The end blocks 123 and 124 are mounted on screws 126 and 127, respectively.

The screws 126 and 127 are caused to turn in unison by a chain 128 which runs on sprockets 129, one of which is shown in FIG. 5 carried by the screws 126 and 127. A crank 131 (FIG. 3) mounted on the screw 127 can be turned to turn the screws 126 and 127 to advance the discriminator blade 121 to a selected position along the carton pick-up assembly 42. Upright plates 132 and 133 (FIG. 6) mounted on the cross bar 122 serve to guide the cartons to the discriminator blade 121. The discriminator blade 121 is adjustably mounted on the cross bar 122. Jack screws 134 and 136 threaded in a flange 137 (FIG. 5) of the discriminator blade and bearing on the cross bar 122 can be turned to adjust the discriminator blade toward and away from the roll 83. Lock screws 138 and 139 mounted in the discriminator blade 121 extend through slots 141 and 142 (FIG. 6), respectively, in an extension plate portion 143 of the cross bar 122, and nuts 144, one of which is shown in FIG. 5, mounted on the lock studs 138 and 139 lock the discriminator blade 121 in adjusted position on the cross bar 122. A limit switch 145 is mounted on a bracket 1451 carried by the cross bar 122. A switch actuator 1452 of the limit switch 145 can be engaged by one of the cartons approaching the pick-up section 42 to indicate that cartons are available for withdrawal by the vacuum cups.

The leading carton is advanced between the discriminator blade 121 and the roll 83. The roll 83 is rotatably mounted on a shaft 146 (FIG. 5) carried between arms 147 and 148 (FIG. 3) of a carton guide 149. The guide 149 is mounted on cross frames 151 (FIG. 5) and 152 (FIG. 3) of the frame 75.

After the carton 71 has passed beneath the discriminator blade 121, it passes over driven lower crusher rolls 153 and 154 (FIG. 6) and under upper crusher rolls 156 and 157. The crusher rolls squeeze outer edges of the flaps of the carton 71 so that edges of the major flaps can overlap properly as the major flaps are glued in place, as will be described in greater detail hereinafter. The driven crusher rolls 153 and 154 are mounted on a shaft 158. The shaft 158 carries a

sprocket 159 on which a chain 161 (FIG. 3) runs. The chain 161 also runs on a sprocket 162 carried by the shaft 116 so that the shaft 158 is driven in timed relation to the shaft 116. The upper crusher roll 156 (FIG. 6) is rotatably mounted on a support bracket 163 carried by a transverse frame 164, and the upper crusher roll 157 is similarly mounted on a support bracket 165 carried by the transverse frame 164.

The transverse frame 164 includes spaced bars 166 and 167 (FIG. 3). Threaded studs 168 and 169 (FIG. 6) mounted on the bracket 163 extend between the bars 166 and 167 and extend through openings (not shown) in plates 171 and 172 on upper and lower sides of the transverse frame 164. Nuts 173 (FIG. 7) threaded on the studs 168 and 169 can be adjusted to adjust the upper crusher roll 156 toward and away from the driven crusher roll 153. The left hand end of the frame bar 166, as shown in FIG. 6, is slidably mounted for up and down movement between an upright frame 174 and a plate 176 attached thereto. The right hand end of the frame bar 166 is similarly mounted between an upright frame 177 and a plate 178 attached thereto. The frame 164 is supported by upright rods 179 and 181 connected thereto by clevises 182 and 183, respectively. The rods 179 and 181 are supported by clamps 1821 and 1831 (FIG. 3) mounted on the frames 174 and 177, respectively.

After the carton passes the crusher rolls, it passes under a printing roll 186 mounted on a shaft 187. An inking roll 188 mounted on a shaft 189 inks appropriate indicia (not shown in detail) on the printing roll so that indicia is printed on the carton as it passes through the carton pick-up and crusher section 42. The shafts 187 and 189 carry sprockets 191 and 192, respectively, on which a chain 193 runs. The chain 193 also runs on a sprocket 194 (FIG. 4) carried by the shaft 158 so that the printing roll 186 (FIG. 2) and the inking roll 188 are driven in timed relation to carton advance. A switch operating cam 195 (FIG. 4) mounted on the shaft 187 engages a switch actuator 1950 of a limit switch 1951 for stopping the chain 193 when the carton has been driven past the printing roll 186.

After passing the printing roll 186 (FIG. 2), the carton passes over a driven diverter roll 196 and under hold-down rolls 197 and 198 (FIG. 8). The roll 196 includes a shaft portion 199 (FIG. 4) on which a sprocket 200 is mounted. The chain 193 runs on the sprocket 200 as shown in FIG. 4 so that the diverter roll 196 is driven in timed relation to carton advance. The hold-down roll 197 (FIG. 8) is mounted on a sliding frame 202 supported by a rod 203. The sliding frame 202 can slide up and down along a guide frame 204 carried on a cross frame 206. Plate portions 207 and 208 of the sliding frame 202 run on opposite sides of the guide frame 204. A clamp 209 supports the upper end of the rod 203. The hold-down roll 198 is similarly mounted on a guide frame 211 (FIG. 3). A bar 212 connects an operating lever 213 (FIG. 8) of the clamp 209 with an operating lever 214 of a clamp 216 (FIG. 3) associated with the guide frame 211.

As shown in FIG. 8, a swinging guide 217 is pivotally mounted on a shaft 218, which is carried by the sliding frame 202. The shaft 218 also is the shaft on which the roll 197 turns. A roller 219 (FIGS. 8 and 9) rotatably mounted on the crank guide 217 normally runs on the diverter roll 196. However, when the carton passes between the diverter roll 196 and the hold-down rolls 197

and 198, the swinging guide 217 is swung upwardly to the dot-dash line position shown in FIG. 8 at 217A.

The carton passes from the diverter roll 196 into a swinging frame or tilt table 221. The swinging frame 221 is mounted on a cross shaft 222, which is pivotally mounted on the frame 75. The swinging frame 221 is generally of U-shape and includes main frames 223 and cantilever frames 224 spaced therefrom to form a pocket into which the carton is advanced. When the swinging frame 221 is in position to receive a carton, one of the frames 224 engages a switch operator 225 of a limit switch 2251. The carton is gripped between idle rolls 226 rotatably mounted on the cantilever frames 224 and driven rolls 227 mounted on a shaft 228. As shown in FIG. 3, a sprocket 2281 mounted on the shaft 228 is driven by the chain 193 so that the rolls are driven in timed relation to the carton advance. The shaft 228 is rotatably mounted on the frame 75. As the carton enters the swinging frame 221, the carton engages a switch actuator 229 (FIG. 8) to actuate a limit switch 230. When the carton has fully entered the swinging frame 221, the swinging guide 217 and another similar swinging guide 231 (FIG. 3) swing down to the full line position of FIG. 8 to hold the carton in the swinging frame. When the carton is required, the swinging frame 221 is swung to the dot-dash line position indicated at 221A in FIG. 2, and the carton is released to slide over the diverter roll 196 and down a chute 233 including support members 2331 and side guides 2332. The swinging frame 221 is swung between the full line position and the dot-dash line position of FIG. 2 by the action of hydraulic cylinders 234 provided with piston rods 2341.

The carton 71 falls to the full line position of FIG. 10 (dot-dash line position of FIG. 14) where it is supported on horizontal rails 236 and 2361 (FIG. 10) at a carton erecting station. When the carton 71 has fallen to this position it engages a switch operator 237 of a limit switch 2371 (FIG. 11) to actuate the limit switch 2371. Stops 238 and 239 (FIG. 14) mounted on side guides 240 and 2401, respectively, arrest advance of the carton. The rails 236 and 2361 are supported on a main framework 2381 and a main framework 2391, respectively. At the carton erecting station, the carton is erected by the action of carton erecting plow assemblies 241 and 242 mounted on the main frameworks 2381 and 2391, respectively.

The carton 71 is of substantially usual form and, as shown in FIG. 13, includes four body walls 243, 244, 246, and 247. At one end are major flaps 248 and 249 and minor flaps 251 and 252. At the other end are major flaps 253 and 254 and minor flaps 256 and 257.

CARTON ERECTING PLOW ASSEMBLY

The plow assembly 241 (FIGS. 10 and 11) is supported on a plate 259, which is a part of the main framework 2381. The plow assembly 242 (FIG. 14) is supported on a plate 2591, which is a part of the main framework 2391. The plow assemblies 241 and 242 are similar in structure and operation, and only the structure of the plow assembly 241 will be described in detail. The plow assembly 241 includes a first lever 261 (FIG. 10) pivotally mounted on a pin member 262 and a second lever 263 pivotally mounted on a pin member 264. The pin members 262 and 264 are carried by a bracket 266 attached to the plate 259. A link 267 con-

ncts right hand ends of the levers 261 and 263. The link carries a link head portion 270. An actuator head 269 is carried by the link 267. The actuator head 269 includes a body of generally angle shape including a first flange 271 attached to the link head portion 270 and an outwardly extending second flange 272. A roller 273 (FIG. 11) is rotatably mounted on a bracket 274 mounted on the flange 272. An arm 276 of the lever 261 (FIG. 10) is pivotally connected to a piston rod 277, which is actuated by a cylinder 278. The cylinder 278 is swingably mounted on a bracket 279 attached to the plate 259.

When the carton 71 is at the carton erecting station as shown in full lines in FIG. 10, the plow assembly 241 is lowered to the dot-dash line position indicated at 241A. The actuator head 269 engages the major flap 248 to cause downward swinging of the major flap 248, the minor flap 252 and the major flap 249 to the positions indicated at 248A, 252A, and 249A in FIG. 10. The minor flap 251 is not swung downwardly, but an edge of the minor flap 251 is caught between the flange 271 of the actuator head 267 and the link head 270 in a slot 281 therebetween. The major flap 249 engages a switch operator 2810 of a limit switch 2811 (FIGS. 11 and 12) when swung downwardly.

The carton 71 is advanced to be erected by action of conveyors 282 and 283 (FIG. 14), which form a first conveyor assembly. The conveyor 282 is supported on a frame plate 284 (FIG. 10), which is a part of the main framework 2381, and the conveyor 283 is supported on a frame plate 285, which is a part of the main framework 2391. The conveyors 282 and 283 are similar in construction, and only the conveyor 282 will be described in detail. The conveyor 282 runs on sprockets 286 and 287 (FIG. 10), which are rotatably mounted on the plate 284. The conveyor 282 also runs on a track assembly 288 (FIG. 14) attached to the plate 284. Flights 289 and 390 (FIG. 10) of the conveyor are advanced by the conveyor 282. The conveyor 282 is driven by a drive unit 291 which drives a belt 292 running on a pulley 293. The pulley 293 is mounted on a shaft 284 which carries a pulley 296 that drives a belt 297. The belt 297 drives a pulley 298 mounted on a shaft 299, which carries the sprocket 287. The flight 289 is advanced from the position shown in FIG. 10 to the position shown in FIG. 11 to advance the carton while the trailing minor flap 251 is restrained by the plow assembly 241 as the plow assembly 241 swings upwardly to the FIG. 11 position to cause erecting of the carton to the position shown in FIG. 11. When the carton is erected, the body of the carton 71 is between the lower rails 236 and 2361 and upper rails 300 and 3001, and the carton 71 engages a switch actuator 301 of a limit switch 302 (FIGS. 11 and 14) which indicates that the carton has been erected. The plow assembly 241 is then raised to the full line position of FIG. 10 by action of the cylinder 278 to release the trailing minor flap 251 and to fold the upper major flap 248 upwardly to the position shown at 248B in FIG. 11. A limit switch actuator 3021 (FIG. 10) of a limit switch 3022 is engaged by one of the flights of the first conveyor assembly when at a home position in the manner the flight 290 is shown in FIG. 10.

When the carton 71 has been erected, it is advanced to the right as shown in FIG. 1 by conveyors 304 and 306 (FIG. 14), which are mounted on the frame plates 259 and 2591, respectively. The conveyors 304 and

306 form a second conveyor assembly and are similar in construction. Only the conveyor 304 will be described in detail. The conveyor 304 runs on a sprocket 3060 (FIG. 1) rotatably mounted on the plate 259 and on a second sprocket 3061 carried by a shaft 307 rotatably mounted on the plate 259. The shaft 307 carries a pulley 308 which is driven by a belt 309. The belt 309 is driven by a pulley carried by a shaft 311 which is driven by a pulley 3111. The pulley 3111 is driven by a belt 3112 which runs on a pulley 3113 carried by a shaft 3114 driven by a drive unit 313.

The conveyor 304 travels on tracks 314 and 316 (FIG. 16) mounted on the plate 259. Flights 3041 (FIG. 10) are carried by the conveyor 304. Flights 3061 are carried by the conveyor 306. The flights 3041 and 3061 engage the carton 71 to advance the carton. When the conveyors 304 and 306 are in a home position, shown in FIG. 14, a flight 3061A engages a switch actuator 3062 of a limit switch 3063. The carton 71 is advanced past upper and lower rear flap guides 317 and 318 mounted on the main framework 2391 and upper and lower front flap guides 319 and 321 mounted on the main framework 2381. Details of construction of the front flap guides 310 and 321 are shown in FIGS. 15 and 16. The upper front flap guide 319 includes an elongated body 322, which extends parallel to the direction of carton movement, and a head 323, which extends outwardly and downwardly therefrom. The body 322 is carried by crank arms 324, 325, and 326, which are carried by a shaft 327. The shaft 327 is rotatably mounted in bearings 328 and 329 attached to frame members 331 and 332, respectively, which are a part of the main framework 2381. As the carton 71 is advanced, the major flap 248 engages the head 323 and is folded upwardly to the position shown in FIG. 16.

The lower front flap guide 321 includes an elongated body 333, which extends parallel to the direction of carton advance, and a head end portion 334, which extends upwardly and outwardly as shown in FIGS. 15 and 16. When the carton 71 is advanced, the major flap 249 engages the head 334 and is folded downwardly to the position shown in FIG. 16. The body 333 (FIG. 15) is mounted on cranks 336, 337, and 338, which are carried by a shaft 339. The shaft 339 is rotatably mounted in bearings 341 and 342 mounted on the frames 331 and 332, respectively. The rear flap guides 317 and 318 (FIG. 14) are similarly mounted and operate similarly to fold the other major flaps of the carton up and down away therefrom.

The front flap guides 319 and 321 are normally held in the position shown in FIG. 15 and in full lines in FIG. 16 by a tension spring 3361. The lower end of the tension spring 3361 is attached to a pin 3371 carried by the frame 332. The upper end of the spring 336 is attached to a pin 3381 carried by an upright link bar 3391. A crank 340 (FIG. 15) is mounted on the shaft 327 and is pivotally connected to a flange 3401 (FIG. 16) at the upper end of the link bar 3391 by a pivot pin 3422. A crank 343 is mounted on the shaft 339 and is pivotally connected to the lower end portion of the upright link bar 3391 by a pivot pin 344. When a crank 346 mounted on the shaft 327 is swung from the full line position of FIGS. 15 and 16 to the dot-dash line position indicated at 346A in FIG. 16, the front flap guides 319 and 321 are swung to the positions shown in dot-dash lines in FIG. 16 at 319A and 321A, respectively,

at which the carton flaps 248 and 249 are released for ease in clearing a carton from the machine at this point, if desired. When the crank 346 is released, the link bar 3391 is urged to the position shown in FIGS. 15 and 16 in which an angle member 347 (FIG. 15) attached thereto engages a stop bar 348 attached to the frame 332.

The conveyors 304 and 306 (FIG. 14) advance the carton 71 to the position shown in double-dot-dash lines at 71B in FIG. 14, which is a loading station. The carton 71 is also shown at the loading station in FIGS. 18 and 35 and at 71B in FIG. 19.

FRONT FLAP CLOSING ASSEMBLY

As the carton approaches the loading station, the minor flap 252 engages a horizontal plate 348 to be folded to the closed position shown in FIG. 18. The plate 348 includes a camming face 349 against which the minor flap 252 is folded. The horizontal plate 348 is mounted on a swinging plate 351, which is rotatably mounted on an upright pivot 353 carried by the frame 331, which is a part of the main framework 2381. The horizontal plate 348 can be adjustably positioned on the swinging plate 351 by means of adjustment screws 356 and 357 threaded in the horizontal plate 348 and rotatably mounted on the swinging plate 351. The horizontal plate 348 is held in adjusted position by fasteners 3561 and 3562 (FIG. 18). The swinging plate 351 is held in the position shown in FIG. 18 by a clamp 3571 mounted on the frame 332. The swinging plate 351 and elements carried thereby can be swung outwardly (counterclockwise as shown in FIG. 18) to permit release of a carton 71 at the loading station if desired to clear the machine. As the carton approaches the loading station 71B (FIG. 14), it passes under a limit switch actuator 3576 of a limit switch 3572. When the carton reaches the loading station it engages a switch actuator 3573 of a limit switch 3574, and the activator 3576 of the limit switch 3572 falls from the carton.

When the carton 71 has reached the loading station, the minor flap 251 is closed by a flap closing assembly 358 (FIGS. 17 and 18) mounted on the horizontal plate 348. The flap closing assembly 358 includes a lever member 359 pivotally mounted on a pivot pin 361 carried by the horizontal plate 348. The lever member 359 swings between a retracted position shown in dot-dash lines at 359A in FIG. 18 and an operative position shown in full lines. The lever member is in the retracted (dot-dash line) position 359A as the carton 71 is advanced to the loading station. Then, when the carton 71 is at the loading station as shown in FIG. 18, the lever member 359 is swung to the full line position to fold the minor flap 251 to the closed position shown. A flange member 361 mounted on the lever member 359 first engages and folds the minor flap 251, and a roller 362 rotatably mounted on the lever member 359 completes the folding. The lever member 359 is actuated by cylinder 363, which is swingably mounted on the horizontal plate 348. A crank 364 is pivotally connected to a piston rod 366, which operates in the cylinder 363. The crank 364 swings on a pivot pin 367 mounted on the horizontal plate 348. An adjustable length link 368 connects the crank 364 to the lever member 359. As shown in FIG. 18, free edges of the minor flaps 251 and 252 are spaced when in closed position.

BOX HOLDING ASSEMBLY

The carton is held at the loading station by box holding assemblies 9001, one of which is shown in FIGS. 20 and 21. The assembly 9001 is mounted on a plate 9002, which is adjustable lengthwise of the frame plate 259. A handle 9003 (FIG. 21) mounted on the plate 9002 is slidable along a slot 9004 (FIG. 20) in the frame plate 259. Fasteners 9006, which are mounted on the plate 9002 and extend through the slot 9004, anchor the plate 9002 in adjusted position. A box holding swinging frame 9007 is carried by a shaft 9008 which is pivotally mounted between the plate 9002 and an outer plate 9009. The plate 9009 is carried by a bracket 9011 (FIG. 21) attached to the plate 9002. A crank 9012 is mounted on the shaft 9008 and is pivotally connected to a piston rod 9013. The piston rod 9013 works in a cylinder 9014, which is pivotally mounted on the plate 9002. The box holding frame 9007 can swing between the full line position of FIG. 20, in which it engages the carton 71, and a dot-dash line retracted position shown at 9007A. When the box holding swinging frame is at the dot-dash line position 9007A, it engages a switch actuator 9016 of a limit switch 9017.

STACK SUPPORTING TONGUE ASSEMBLY

When the carton 71 is at the loading station, a stack supporting tongue 369 is extended into the carton 71 (FIGS. 14, 19, and 23) through the space between the flaps 251 and 252 (FIG. 23). The tongue 369 is formed of spring metal and, as shown in FIG. 26, is normally of arc shape in section. A resilient bumper 371 (FIG. 24) is mounted on the free end of the tongue 369. The opposite end of the tongue 369 is attached to a wheel 372 by fasteners 3721 as shown in FIG. 25. The wheel 372 is mounted on a shaft 373 (FIG. 23) rotatably mounted on a wheel table 374. The wheel table 374 is adjustably mounted on a swinging table 376. Rollers 3761 carried by and underlying the wheel table 374 run on the swinging table 376 so that the wheel table 374 can be adjusted to the right or left as shown in FIG. 22. A lock bolt 3762 mounted on the swinging table 376 is received in a slot 3763 in an angle bracket 3764 attached to the wheel table 374 and can lock the wheel table 374 in position. One end of the swinging table 376 is rotatably mounted on an upright bearing link 377 carried by a frame 3771, which is a part of the main framework 2391. The other end of the swinging table 376 can be releasably attached to an upright frame 3772 by an appropriate clamp (not shown). The swinging table 376 normally is in the position shown in FIGS. 22, 23, and 24 but can be swung back counterclockwise as shown in FIG. 23 to permit access to the carton 71 at the loading station.

A rotary motor 378 (FIGS. 22 and 24) is mounted beneath the wheel table 374 and drives the shaft 373 to turn the wheel 372. The wheel 372 is supported on rolls 379 carried by brackets 381 mounted on the wheel table 374. Idle rolls 383, 384, 386, 387, (FIG. 23) 388, 389, and 391 are rotatably mounted on shafts 3831 (FIG. 24), 3841, 3861, 3871, 3881, 3891 (FIG. 22), and 3911, respectively, carried by the wheel table 374 and engage the tongue 369 to hold the tongue 369 against the wheel 372. As the tongue 369 leaves the wheel 372, the tongue 369 passes between idle guide rolls 393 and 394 (FIG. 23) mounted on shafts 3931 and 3941 carried by the wheel table 374. A stop 396

mounted on a spoke 397 of the wheel 372 can engage a stop member 398 mounted on the wheel table 374 to limit swinging of the wheel 372 to a little under one full turn. The motor 378 can turn the shaft 373 and the wheel 372 to advance the tongue 369 from a retracted position shown in FIGS. 14 and 24 to an extended position shown in FIG. 35 and in dot-dash lines at 369A in FIGS. 23 and 19.

STACK ADVANCING ASSEMBLY

When the tongue 369 has been extended to the FIG. 35 position, a stack 401 of flat articles can be advanced into the carton 71 by a stack advancing or inserting assembly 402. The stack 401 is formed on an appropriate stack forming machine 403 (FIG. 19), only a portion of which is shown. The stack 401 is delivered by the machine 403 onto horizontal guides 406 and 407 (FIGS. 19 and 33). The guides 406 and 407 are supported on upright guide plates 408 and 409 (FIG. 19), respectively, which are mounted on a framework 411 of the stack forming machine 403. A stack pusher assembly 412 (FIG. 19) pushes the stack from the guides 406 and 407 into the stack advancing assembly 402. A piston 413 (FIG. 58) mounted on a piston rod 414 operates in a cylinder 416 to advance the pusher assembly 412 (FIG. 19). The pusher assembly 412 can be generally similar to the pusher assembly shown in Staap et al. application Ser. No. 318,189, filed Dec. 26, 1972. Upright pusher bars 4161 can engage the stack. The pusher bars 4161 are mounted on a cross frame 4162 to which the piston rod 414 is attached. The cross frame 4162 is mounted on sliding blocks 4163 and 4164, which are slidably mounted on horizontal guide bars 4166 and 4167, respectively. When the pusher bars 4161 are in advanced position, the cross frame 4162 engages a switch actuator 4171 of a limit switch 4172. The stack is advanced into engagement with an upright stop plate 415 (FIGS. 19, 33, and 34). The plate 415 is mounted on a lower plate 4151 (FIGS. 33 and 34) and an upper plate 4152 (FIGS. 19 and 37A) which are mounted on screw supports 4153 (FIGS. 33 and 37A), 4154 (FIGS. 19 and 37A) and 4155 (FIG. 37A). A chain 4156 runs on sprockets carried by the screw supports. The chain 4156 also runs on a sprocket 4157 mounted on a shaft 4158 which carries a crank 4159. The crank 4159 can be turned to adjust the position of the stop plate 415.

The stack advancing assembly 402 includes a main shaft 418 (FIG. 33) rotatably mounted on bearings 419 and 421 carried by support plates 422 and 423 which are carried by frame elements 424 and 425, respectively, of the framework 411 of the stack forming machine. Brackets 426 and 427 are mounted on the main shaft 418. The brackets 426 and 427 support parallel guide rods 428 and 429. In addition, a threaded shaft 430 is rotatably supported between the brackets 426 and 427. Clamp bars 431 and 432 (FIGS. 19 and 33) are slidably mounted on the guide rods 428 and 429, respectively. The clamp bars 431 and 432 are held in selected position on the guide rods 428 and 429 by action of clamping bolts 433 (FIG. 34). Side frames 434 and 436 are attached to the clamp bars 431 and 432. Cross plates 437 and 4371 span the side frames 434 and 436. A guide plate 438 (FIG. 34) also spans the side frames 434 and 436. The threaded shaft 430 is in threaded relation to the side frames 434 and 436 so that, when the threaded shaft 430 is turned by turning

of a knurled collar 4301 mounted thereon, the side frames are moved along the guide rods 428 and 429 to adjust the position of the stack advancing assembly. Cross plates 439 and 441 are attached to the side frames 434 and 436, respectively, and extend outwardly therefrom. Side frames 442 and 443 (FIG. 34) are attached to the cross plates 439 and 441, respectively, and extend parallel to the side frames 434 and 436 spaced therefrom. A cross plate 445 spans the side frames 442 and 443 adjacent free ends thereof.

Guide plates 446 and 447 (FIG. 36) are attached to the side frames 442 and 443, respectively. A stack support plate 449 (FIGS. 19, 34, and 36) is mounted on the guide plates 438. Stack support brackets 451 and 452 (FIG. 36) are supported on the side plates 446 and 447, respectively. The stack 401 (FIG. 35) is pushed onto the stack support plate 449 and the stack support brackets 451 and 452 by the pusher assembly 412 (FIG. 19).

As shown in FIGS. 34, 35, and 37, a shaft 454 is rotatably mounted in brackets 456 mounted on the plate 438. A crank 457 is attached to the shaft 454. A piston rod 458 (FIGS. 21 and 34) carries a head 459 which is pivotally connected to the crank 457. The piston rod 458 is carried by a piston 460 (FIG. 58) which works in a cylinder 461. The cylinder 461 is pivotally supported on a bracket 462 (FIG. 34) mounted on a cross bar 463 which spans the side frames 434 and 436 as shown in FIG. 33.

Brackets 466 (FIG. 37) are mounted on the shaft 454. The brackets 466 include inwardly extending stack gripping portions or flaps 467. In addition, the crank 457 includes an inwardly extending stack gripping or flap portion 468. Similarly, brackets 469 (FIG. 34) mounted on the cross plate 445 pivotally support a shaft 471 on which a crank 472 and stack engaging brackets 473 are mounted. A piston rod 474 carries a head 476 which is pivotally connected to the crank 472. The piston rod 474 carries a piston 4741 (FIG. 58) which works in a cylinder 477. The cylinder 477 (FIG. 34) is pivotally mounted on a bracket 478 carried by a cross bar 479, which spans the side frames 442 and 443.

Angle shaped cranks 481 and 482 (FIG. 34) are pivotally mounted on stub shafts 483 and 4831 (FIG. 33) carried by the cross plates 439 and 441, respectively. A piston rod 484 carries a head 486 which is pivotally supported between the cranks 481 and 482. A piston 487 (FIG. 58) carried by the piston rod 484 works in a cylinder 488 pivotally mounted between the plates 439 and 441 (FIG. 33). The cranks 481 and 482 can be swung between the FIG. 35 and FIG. 34 positions by action of the cylinder 488.

Stationary sprocket members 491 and 492 (FIG. 33) are mounted on the stub shafts 483 and 4831. The sprocket members 491 and 492 are attached to the cross plates 439 and 441, respectively, so that the sprocket members 491 and 492 do not turn on the stub shafts 483 and 4831. A shaft 493 (FIG. 34) is pivotally mounted adjacent ends of the cranks 481 and 482. Sprockets 494, one of which is shown in FIG. 34, are mounted on the shaft 493. Cranks 496 and 497 are also mounted on the shaft 493 to swing with the sprockets 494. Chains 498 connect the sprockets 494 with the sprocket members 491 and 492. The pitch diameter of each of the sprockets 494 is one-half the pitch diameter of each of the sprocket members 491 and 492 so that,

when the cranks 481 and 482 are swung between the FIG. 35 and the FIG. 34 positions, the cranks 496 and 497 are swung between the FIG. 35 and FIG. 34 positions. A link 499 is pivotally mounted on the shaft 493. A shaft 501 mounted on the link 499 pivotally supports outer ends of links 502 and 503. Inner ends of the links 502 and 503 are pivotally supported on stub shafts 504 mounted on the cross plates 439 and 441. An upright bar 507 is mounted on a shaft 508 which spans free ends of the cranks 496 and 497. Links 509 and 511 link the shaft 501 and a shaft 512 which extends through the upright bar 507. A head 513 is mounted on the upper end of the upright bar 507. The head 513 is in a lowered position underlying the stack support plate 449 and the brackets 451 and 452 when the cranks 481 and 482 are in the FIG. 35 position. When the head 513 is fully lowered, the crank 481 engages a switch operator 5131 of a limit switch 5132. The cranks 481, 482, 496, and 497, the links 499, 502, 503, 509, and 511, and the upright bar 507 form parallelogram linkages holding the upright bar 507 in parallelism to the side frames 434, 436, 442, and 443 and spaced therebetween. The distance between the shafts 501 and 512 is equal to the distance between the shaft 501 and the stub shafts 504 and is also equal to the distance between the shafts 493 and 508 and the distance between the shaft 493 and the stub shafts 483 and 4831 so that the upright bar 507 travels in a straight line in alignment with the axes of the stub shafts 504 and of the stub shafts 483 and 4831, and the shafts 512 and 508 and the stub shafts 504, 483, and 4831 remain in alignment as the head 513 is advanced and retracted. When the stack 401 has been advanced onto the stack support plate 449 and the brackets 451 and 452, the head 513 is raised sufficiently to raise the upper face of the stack against the stack gripping flaps of the brackets 466 and 473 and the outwardly extending portions of the cranks 457 and 472 by action of the cylinder 488. When the stack is brought into such engagement, the stack engages a switch operating cam 5101 (FIG. 38) which is pivotally mounted on the shaft 471. A transverse pin 5102 mounted in one of the brackets 473 extends into a transverse bore 5103 in the cam 5101 so that the cam 5101 can swing upwardly without turning of the bracket 473 to advance a switch operator 5104 of a limit switch 5106. Then, the stack advancing assembly is swung to the position at which the side frames are indicated at 434A and 442A in dot-dash lines in FIG. 35 at which free ends of the side frames are opposite the carton 71 at the loading station. The assembly is swung by action of a cylinder 5131 (FIGS. 33 and 34). A piston rod 513R works in the cylinder 5131. A crank 5133 is pivotally connected to the piston rod 513R. The crank 5133 is mounted on the shaft 418. When the crank 5133 is swung to the dot-dash line position 5133A of FIG. 35, it engages a switch operator 5134 of a limit switch 5136. When the assembly 402 approaches its upright position, the clamp bar 432 engages a switch activator 5137 of a limit switch 5138. When the assembly 402 reaches upright position, a switch operator 513L of a limit switch 5141 is engaged by the cross plate 4371. When the stack advancing assembly is in the position at which the side frames are indicated at 434A and 442A in dot-dash lines in FIG. 35, the piston rods 458 and 474 (FIG. 34) are drawn inwardly of the cylinders 461 and 477, respectively, to cause the brackets 473 and 466 and the cranks 457 and

472 to release the stack, and the head 513 is advanced further along the stack advancing assembly by action of the cylinder 488 to advance the stack into the carton 71 where the tongue 369 and the bumper 371 thereof catch the leading flat article of the stack to keep the stack erect as the stack is loaded into the carton 71. As the stack advances into the carton, the tongue 369 is retracted until the tongue has been fully retracted from the carton and the stack has been fully advanced into the carton. When the head 513 is fully advanced, the link 511 engages a switch actuator 5139 of a limit switch 5140.

When the stack 401 has been advanced into the carton 71, the minor flaps 256 and 257 (FIG. 19) are closed by action of an upstream flap closing assembly 516 (FIGS. 14, 27, 28, and 29) and a downstream flap closing assembly 517 (FIGS. 19 and 31). The head 513 (FIG. 35) is withdrawn and, as it is withdrawn, a switch actuator 514L of a limit switch 5142 is displaced to indicate the head 513 is descending.

UPSTREAM FLAP CLOSING ASSEMBLY

The upstream flap closing assembly 516 (FIGS. 27, 28, and 29) is mounted on upright frames 521 and 522 (FIGS. 27 and 28), which are a part of the main framework 2391. A lower frame plate 523 is mounted on the frames 521 and 522. An upper frame plate 524 is attached to the upright frame 521 and is supported in spaced parallel relation to the lower plate 523 by a bracket plate 526, a cylinder 527 is pivotally mounted on a bracket 528 (FIGS. 27 and 29) attached to the bracket plate 526. A piston rod 529 having a piston 530 (FIG. 58) which works in the cylinder 527, carries a head 531 (FIG. 29) which is pivotally connected to a link 532. The link 532 is pivotally mounted between the plates 523 and 524. A second link 533 is also pivotally mounted between the plates 523 and 524. The links 532 and 533 are mounted on shafts 5321 and 5331, respectively, which span the plates 523 and 524 so that the links 532 and 533 can pivot only in a horizontal plane. Outer ends of the links 532 and 533 pivotally support a housing 536 which includes upper and lower spaced plates 5361 and 5362. The housing 536 can be swung between an operative position shown in FIG. 29 and a retracted position shown in FIG. 14 by action of the cylinder 527. The housing 536 is in the retracted position shown in FIG. 14 as the carton is advanced to the loading station. Then, when the carton 71 is at the loading station, the housing 536 is advanced to the operative position of FIG. 29. A flap closing head 538 is pivotally mounted on the housing 536. The flap closing head 538 can be swung from the full line position of FIG. 29 to the dot-dash line position 538A by action of a cylinder 539, which is pivotally mounted on a bracket 451 carried by the housing 536. A crank member 542 is pivotally connected to a piston rod 543 carried by a piston 5431 (FIG. 58) which works in the cylinder 539. The crank 542 (FIG. 29) is pivotally mounted inside the housing 536 on a pivot pin 544. Links 546 and 5461 (FIG. 30) connect the crank 542 to a lug 5462 attached to the flap closing head 538. When the stack has been loaded in the carton 71, the flap closing head 538 is swung from the full line position of FIG. 29 to the dot-dash line position indicated at 538A to close the minor flap 256.

When the flap closing head 538 is in the full line position of FIG. 29, it engages a roller 5469 carried by a

bell crank 547 to draw a control wire 548, which is attached to the bell crank 547, outwardly of a sleeve 549, which is attached to the housing 536. The control wire 548 operates a valve 551 (FIG. 27) mounted on the main framework 2391. The valve 551 permits movement of the piston rod 529 only when the head 538 is retracted. As the crank 542 (FIG. 29) is swung, an elongated upright first pin 5511 swings along a curved slot 5512 in the plate 5361 from the full line position in FIG. 30 to a dot-dash line position indicated at 5511A. When this pin is at the position 5511A, it engages a switch operator 5513 of a limit switch 5514 to actuate the limit switch 5514 when the flap closing head 538 is at the dot-dash line position 538A of FIG. 29. The limit switch 5514 is mounted on a bracket 5516 attached to the plate 5361.

DOWNTREAM FLAP CLOSING ASSEMBLY

The downstream flap closing assembly 517 includes a track 553 (FIG. 19) mounted on short frames 554, 555, 556, and 5561 attached to elements of the main framework 2391. A slide bar 557 is mounted for sliding lengthwise of the track 553. Rollers 5571 and 5572 mounted on the track 553 are received in grooves 5573 (FIG. 32) in the slide bar 557 to hold the slide bar 557 and the track 553 in parallelism. A block 558 (FIGS. 19 and 31) is attached to the slide bar 557. A piston rod 559 carries a head 561 which is connected to the block 558. The piston rod 559 carries a piston 560 (FIG. 58) which works in a cylinder 562. The cylinder 562 is mounted on a bracket 5621 (FIG. 19) attached to the track 553. A flap closing head 563 is hinged to the slide bar 557 and can swing between an open position shown in full lines in FIG. 31 and a flap closed position shown in full lines in FIG. 19. A lug 566 on the flap closing head 563 is pivotally connected to a head 567 of a piston rod 568. The piston rod 568 carries a piston 569 (FIG. 58) that works in a cylinder 571, which is pivotally mounted on the slide bar 557. The flap closing head 563 is swung from the full line position of FIG. 31 to the full line position of FIG. 19 when the stack has been advanced into the carton 71, and the flap closing head 563 closes the minor flap 257. A control wire 573 is connected to the flap closing head 563 and is moved lengthwise of a sleeve 574 by swinging of the flap closing head 563. The control wire 573 is connected to a switch actuator 576 of a limit switch 5761. The sleeve 574 is anchored on a bracket 5741 (FIG. 19) attached to the block 558. When the flap 257 has been closed, the head 513 (FIGS. 33, 34 and 35) of the stack advancing assembly 402 is retracted from the carton 71 by action of the cylinder 488. Then the slide bar 557 (FIG. 19) and the flap closing head 563 are advanced to the position at which the flap closing head is shown in FIG. 19 in dot-dash lines at 563A so that the flap closing head 563A is sufficiently close to the flap closing head 538 of the upstream flap closing assembly 516 that the minor flap 256 can be held by the flap closing head 563 when the carton 71 is advanced to the right as shown in FIG. 19. The slide bar 557 and the flap closing head 563 are advanced by action of the cylinder 562. A rod 578 is connected to the block 558 and moves with the slide bar 557. The rod 578 carries adjustable cam dogs 579 and 581 which operate valves 582 and 583, respectively. The cam dog 579 operates the valve 582 when the slide bar 557 is in the full line position of FIG. 19. The cam dog 581 operates the

valve 583 when the slide bar 557 is in the advanced position at which the flap closing head thereof is shown at 563A in dot-dash lines. When the flap closing head is at the position 563A, the bracket 5741 engages a switch operator 5742 of a limit switch 5743.

BOX GUIDES AND GLUING ASSEMBLY

When the head has been advanced to the position 563A and the tongue 369 has been retracted, the conveyors 304 and 306 (FIG. 14) advance the loaded carton to the right as shown in FIGS. 1 and 19. The minor flaps 256 and 257 ride on and are held closed by the slide bar 557 (FIG. 19) and the track 553. The minor flaps 251 and 252 ride against and are held closed by box guide bars 589 and 591 (FIGS. 1, 39, 40, and 41). The bars 589 and 591 are mounted on shafts 592 and 593, respectively. The shafts 592 and 593 are rotatably mounted in sleeves 5921 and 5931 attached to the frame 331 and to a frame 594, respectively. Clamps 596 and 597 mounted on the frames 331 and 594, respectively, releasably hold the bars 589 and 591 in the position shown in FIGS. 39 and 40. However, if desired, the bars 589 and 591 can be swung out of the way for ease in clearing the machine of a carton if desired. As shown in FIG. 42, a bolt 598 is mounted in and extends radially of the shaft 592 and is releasably received in a slot 5981 in the sleeve 5921 to hold the guide bar 589 (FIG. 40) in position. However, when the clamp 596 is released, the bar 589 and the shaft 592 can be moved outwardly to release the bolt 598 from the slot 5981 so that the bar 589 and the shaft 592 can be swung out of the way of a carton in the machine. The shaft 593 carries a similar bolt 5983 which is received in a similar slot, not shown, in the sleeve 5931.

The carton passes from the bar guides 589 and 591 to gluing assemblies 599, one of which is shown in detail in FIGS. 43, 44, and 45. The assembly 599 includes a frame plate 601 mounted on the upright frame 594. An upright pivot pin 602 (FIG. 44) is mounted on a plate 603 attached to the frame plate 601. A swinging frame 604 is provided with a cylindrical head 606 rotatably mounted on the upright pivot pin 602.

The swinging frame 604 includes a body 607 (FIG. 43), first upright arms 608 and 609 and second upright arms 611 and 612. A guide bar 614 is supported on frame supports 616 (FIG. 45) and 617 (FIG. 44) carried by the body 607. Stationary cantilever rods 618 and 619 are attached to the first upright arms 608 and 609, respectively. Clamps 621 and 622 mounted on the rods 618 and 619 support spring mounts 623 and 624 (FIG. 43), respectively. Glue valve supporting clamps 626 and 627 are carried by the spring mounts 623 and 624, respectively. Glue valves 628 (one of which is shown in FIGS. 46 and 47) are mounted on the clamps 626 and 627 and feed glue to glue heads 631 and 632 (FIG. 43). Flap guide and spring back-up members 633 and 634 are also mounted on the clamps 621 and 622, respectively. Resilient bumpers 636 and 637 mounted on the members 633 and 634 limit outward swinging of the spring mounts 623 and 624, respectively. Cantilever frames 638 and 639 (FIG. 45) are mounted on the second upright arms 611 and 612, respectively. Flap guides 641 and 642 are mounted on the cantilever frames 638 and 639, respectively. In addition, hollow brackets 6411 and 6421 are attached to the cantilever frames 638 and 639. The brackets 6411 and 6421 hold

pads 643, one of which is shown in FIG. 47, against which the glue heads 631 and 632 (FIG. 43) are pressed when not engaging a carton flap.

When the carton 71 is advanced past the glue heads 631 and 632 (FIG. 43), the major flaps of the carton are guided to the glue heads 631 and 632 by the flap guides 641 and 642 and by the members 633 and 634. As shown in FIG. 47, each of the glue head supporting clamps carries an obtuse angle shaped guide 646 which directs the major flap to the associated glue head as the major flap 248 is shown in FIG. 47. A second gluing assembly similar to that just described is mounted on the opposite side of the machine for feeding glue to major flaps at the opposite end of the carton. The second gluing assembly differs from that already described chiefly in that the second gluing assembly is mounted on fixed supports instead of being on a pivoted support as is the glue head assembly already described. A guide plate of the second glue head assembly is shown at 614A in FIG. 44.

As the carton passes the glue heads, it engages and actuates switch actuators 647, 648, 649, and 651 (FIG. 44) of limit switches 652, 653, 654, and 656, respectively. When the carton engages the actuator of the limit switch 652, glue is delivered to the glue heads to provide glue on the major flaps opposite the leading minor flaps. When the carton reaches the actuator of the limit switch 653, the delivery of glue is halted to provide no glue on the major flaps opposite the space between minor flaps. Then as the carton advances to clear the actuator of the limit switch 649, delivery of glue is started again to provide glue on the major flaps opposite the trailing minor flaps. When the carton passes beyond the actuator of the limit switch 656, the delivery of glue is again halted as the carton 71 passes beyond the glue assembly.

As the carton 71 leaves the glue heads, it passes to a front cantilever guide member 658 (FIGS. 1, 48, 49, and 50) which holds the minor flaps on the front of the carton closed as the carton is advanced to front flap closing elements 659 and 661 (FIGS. 51 and 52) and rear flap closing members 6591 and 6611 (FIG. 52). The front cantilever guide member 658 is mounted on an angle shaped frame 662 (FIGS. 48, 49, and 50) having a tubular head 663 pivotally mounted on an upright pin 664. The upright pin 664 is carried by a bracket 666 mounted on an upright frame 667. The front cantilever guide member 658 normally is in position shown in FIGS. 49 and 52 but can be swung outwardly for access to a carton. A clamp 668 (FIGS. 48 and 50) holds the front cantilever frame in the normal position. A similar cantilever guide member 669 (FIG. 52) mounted on a frame member (not shown) holds back minor flaps closed as the carton 71 approaches the flap closing members 659, 661, 6591, and 6611. The flap closing members 659 and 661 are supported on horizontal rods 671 mounted on a frame 672. The frame 672 is carried by a sleeve 673 which is pivotally mounted on a pin 674 carried by a bracket 676 mounted on an upright frame 677. A clamp 678 mounted on the frame 667 holds the flap closing members 659 and 661 in the position shown in FIGS. 51 and 52. The flap closing members 6591 and 6611 are carried by horizontal rods 679 mounted on a frame 680. The frame 680 is carried by upright frames 681 and 682. As the carton 71 is advanced past the flap closing members 659, 661, 6591, and 6611, the lower major

flaps are closed and then the upper major flaps are closed. As the major flaps are closed, edge portions thereof overlap, which are the edge portions which were crushed by the crusher rolls 153, 154, 156, and 157 (FIG. 6) of the carton pick-up section 42 (FIG. 2).

COMPRESSION SECTION

As the loaded carton passes to the gluing assemblies 599, it passes to a third conveyor assembly including conveyor chains 701 (FIG. 1) and 702 (FIG. 53), which are supported on frame plates 703 and 704. The conveyor chains 701 and 702 run on outer sprockets 706 and 707, respectively, and on inner sprockets, one of which is shown at 708 (FIG. 1). Flights 709 are carried by the chains 701 and 702. When the conveyor chains are at a home position, one pair of flights is at the position indicated at 709A in which a switch operator 711 of a limit switch 712 is engaged by one of the pair of flights 709A. The conveyor chains 701 and 702 advance the loaded carton into a compression section 713, details of construction of which are shown in FIGS. 53 and 54. The compression section 713 includes a hollow framework including upright frames 716, 717, 718 and 719 linked by appropriate cross frames. Upright conveyor frames 721 and 722 are supported on screw supports 723 (FIG. 54), 724, 726 and 727 carried by cross frames 728 and 729, which span the upright frames 718 and 719. An upper horizontal shaft 731 and a lower horizontal shaft 732 (FIG. 53) are journaled in bearings 733 carried by the upright conveyor frames 721 and 722. Vertical conveyor chains 734 (FIG. 54) and 736 run on sprockets 737 and 738 carried by the upper shaft 731 and sprockets 739 and 741 (FIG. 53) carried by the lower shaft 732. Flights 742 are carried by the conveyor chains 734 and 736, the spacing between flights being a little greater than the height of the loaded carton 71. One of the flights at a height to receive a carton from the conveyor chains 701 and 702 of the third conveyor assembly is indicated at 742A. In a similar fashion, flights 749 are carried by vertical conveyor chains 751, which run on upper sprockets 752 and 753 carried by an upper shaft 754 and lower sprockets 756 and 757 carried by a lower shaft 758. The shafts 754 and 758 are journaled in bearings 759 mounted on upright conveyor frames 761 and 762. The conveyor frames 761 and 762 are supported on cross rods 763 and 764, respectively, and are movable crosswise of the compression section to adjust to the length of the carton 71. A bracket 765 attached to the upright conveyor frame 761 is also attached to the frame 677 of the main framework 2381 (FIG. 1) for automatic adjustment of the conveyor frames 761 and 762 when the main framework 2381 is adjusted. When one of the flights reaches the position indicated at 749A in FIG. 53, at the height at which a carton is received from the chains 701 and 702 of the third conveyor, it engages a switch operator 743 of a limit switch 744.

As the carton 71 is raised in the compression section 713, it passes between rows of rollers 766 which hold the flaps of the carton closed while the glue thereon has time to dry. The rollers 766 are rotatably mounted between upright roller frames 767 and 768 (FIG. 54) and between upright roller frames 769 and 770. The upright roller frames 767 and 768 are carried by cross members 771 and 772 which span the upright conveyor

frames 721 and 722. The upright roller frames 769 and 770 are mounted on cross frames 773 and 774 carried by the upright conveyor frames 761 and 762. As shown in FIG. 55, shafts 776A and 776B, which rotatably support rollers 766A and 766B, are urged inwardly by springs 777A and 777B, respectively. The springs 777A and 777B are mounted on bolts 778A and 778B, which are mounted in collars 779A and 779B carried by the shafts 776A and 776B, respectively. The springs engage the collars and also engage a flange 780 of the upright roller frame 767. Shanks of the bolts 778A and 778B extend through openings 7801A and 7801B in the flange 780. All of the rollers 776 of the compression section 713 are urged inwardly with the exception of the rollers at the upper and lower ends of each row of rollers.

Each filled carton is advanced upwardly by the flights 742 and 749 (FIG. 53) in a stepwise fashion until it reaches a discharge position supported on flights at the position where the flights 742B and 749B are shown in FIG. 53. At this position, the carton engages a switch operator 781 of a limit switch 782.

The loaded carton is then advanced onto a discharge conveyor 783 (FIGS. 1 and 54) by action of a carton ejecting assembly 784 (FIGS. 54 and 54). The carton ejecting assembly 784 includes a carriage 786 slidably mounted on a horizontal shaft 787. A cross bar 788 is carried by the carriage 786. A free end of the cross bar 788 is supported on a bracket 789 (FIG. 53) carried by head members 791 of the upright conveyor frames 761 and 762. The carriage 786 is advanced to the right and left as shown in FIG. 54 by action of a hydraulic cylinder 793. A piston rod 794 operates in the cylinder 793. The piston rod 794 is pivotally connected to a swinging bar 796. The swinging bar 796 is pivotally mounted on a cross frame 797. The swinging bar 796 is constructed to advance the carriage 786 and the cross bar 788 to the right and left as the swinging bar 796 is swung to the right or left. Limit switches 800 and 801 mounted on the cross frame 797 are provided with operators 802 and 803, respectively, which are engaged by the swinging bar 796 when at the limit of its movement to the right or left.

OPERATION

The operation of the machine will now be described with particular reference to FIGS. 56 and 57 which show electrical connections of the machine, FIG. 58 which shows hydraulic connections, FIGS. 59 and 60 which show pneumatic connections, and FIG. 61 which shows vacuum connections.

Electric power is supplied by main leads 807 and 808 (FIG. 56). Air under pressure is supplied by appropriate sources of air under pressure 809 (FIG. 59) and 811 (FIG. 60). When the machine is set in operation, a push button starting switch 812 (FIG. 56) is actuated to close contacts 812A and 812B thereof to energize a control relay 813 causing closing of relay contacts 813A and 813B thereof to connect power leads 814 and 816 to the main leads 807 and 808, respectively. Closing of the contacts 812A also energizes a motor 818. The motor 818 drives a hydraulic pump 819 (FIG. 58) which supplies hydraulic fluid to a pressure line 820, fluid returning through a return line 821. When the motor 818 is energized, contacts of a motor relay 818A (FIG. 56) are closed to form a hold-in circuit for the motor 818. The motor 818 can also be energized by

closing of a push button switch 822. The motor 818 can be stopped by opening of contacts of a push button switch 823. When the motor 818 is energized, a lamp 818B, mounted in parallel therewith, is energized. Lamps 812C and 812D are energized when the switch 812 is actuated. The power to the machine can be cut off by opening of contacts of a push button switch 826 to open contacts 826A and 826B thereof de-energizing the control relay 813 and the motor 818. When the machine is set in operation, a selective on-off switch 827 is closed to energize a motor 828 which powers a vacuum pump 829 (FIG. 61) which impresses a vacuum in a line 832. Contacts 833A of a selective on-off switch 833 (FIG. 57) are closed and contacts 833B of the selective on-off switch 833 are opened to permit operation of a drive for the conveyors of the carton pick-up assembly 42 as will be described in greater detail hereinafter. The motor 120 (FIG. 56) is also energized when the machine is set in operation. The motor 120 drives clutches, to be described hereinafter, to drive the various conveyors. When the starting switch 812 is actuated, contacts 812E (FIG. 57) and 812F are closed and contacts 812G are opened. Contacts 812H and 812J are closed and contacts 812K and 812L are opened. When the machine is set in operation, a selective position inserter control switch 8123 (FIG. 56) is moved to its other position to close contacts 8123A and open contacts 8123B thereof.

When a stack of cartons 71 is disposed in position to be advanced into the carton pick-up assembly 42, the contacts of the limit switch 145 (FIG. 5) are opened to de-energize a motor 834 (FIG. 56). When the contacts of the switch 145 close, the motor 834 is energized to actuate mechanism (not shown in detail) to advance the conveyor 72 (FIG. 2) to bring cartons into position to actuate the switch 145 (FIG. 5).

When the flight 104 (FIG. 5) engages the actuator 1204 of the limit switch 1203, contacts of the limit switch 1203 (FIG. 56) close to energize a solenoid 836. Energizing of the solenoid 836 advances a valve 837 (FIG. 60) to its alternate position to direct air under pressure along a line 8371 into the cylinders 91 to cause the vacuum cups 84 (FIG. 3) and 86 (FIG. 5) to advance into engagement with the leading carton 71A. When the vacuum cups 84 and 86 engage the leading carton 71A, a vacuum is impressed on the interior of the vacuum cups 84 and 86 by the vacuum line 832 (FIG. 61), a valve 838 and a line 839 which leads to the interior of the vacuum cups 84 and 86. When the vacuum is set up inside the vacuum cups 84 and 86, a vacuum operated switch 841 connected to the vacuum line 832 swings to its other position opening contacts 841A (FIG. 56) thereof to de-energize the solenoid 836 and closing contacts 841B thereof to energize a solenoid 842. Energizing of the solenoid 842 moves a valve 843 (FIG. 60) to its alternate position to direct air under pressure through a line 844 to the cylinders 91 causing the vacuum cups to be drawn toward the frame 75 (FIG. 5) to draw the leading carton 71A into position to be engaged by the flights 104 and 106.

When the swinging frame 221 is in the full line position of FIG. 2 ready to receive a carton, the switch actuator 225 (FIG. 8) of the limit switch 2251 is engaged by one of the frames 224 to close switch contacts 2251A (FIG. 57) and to open contacts 2251B thereof. Closing of the contacts 2251A energizes a clutch solenoid 845 which connects the motor 120 to drive the

chain 117 (FIG. 2) causing advance of the flights 104 and 106 (FIG. 3). When the flight 104 reaches the position at which it is ready to pick up the leading carton, the flight 104 engages the switch operator 1202 (FIG. 5) of the limit switch 1201 to close the contacts of the switch 1201 (FIG. 56) to energize a solenoid 846 to move the valve 838 (FIG. 61) to its alternate position to release the vacuum on the vacuum cups 84 and 86. The leading carton is advanced under the discriminator blade 1211 (FIG. 5) and the printing roll 186 (FIG. 3) into the swinging frame 221 where the carton engages the switch actuator 229 (FIG. 8) of the limit switch 230 (FIG. 57) to open contacts 230A, close contacts 230B and 230C, and open contacts 230D thereof. When, 15 after the switch 230 has been actuated, the printing roll shaft 187 (FIG. 4) has reached its home position, the cam 195 engages the switch operator 1950 of the limit switch 1951 to open contacts 1951A (FIG. 57) to de-energize the clutch solenoid 845 and to close contacts 20 1951B and 1951C thereof. Closing of the contacts 1951B energizes a brake solenoid 849 which stops advance of the chain 193 (FIG. 4) and of the chain 117 (FIG. 2).

Closing of the contacts 230C and 1951C, when the 25 machine is ready for a carton to be advanced further, energizes a solenoid 851 (FIG. 57) which moves a valve 852 (FIG. 58) to the position shown at which fluid under pressure is directed from the pressure line 820 through a line 8521 to the cylinders 234 to cause extension of the piston rods 2341 and to swing the 30 swinging frame to the position shown at 221A in FIG. 2 so that the carton falls downwardly to the position at which the carton 71 is shown in FIG. 10. When the carton 71 is at this position, it engages the switch operator 35 237 of the limit switch 2371 to close contacts 2371A (FIG. 57) and open contacts 2371B thereof. Opening of the contacts 2371B de-energizes the solenoid 851. Closing of the contacts 2371A energizes a solenoid 853 which advances the valve 852 (FIG. 58) to its alternate 40 position to direct hydraulic fluid under pressure along a line 854 to withdraw the pistons 2341 of the cylinders 234 and cause return of the swinging frame 221 to the full line position of FIG. 2. As shown in FIG. 58, check and throttle valve assemblies 856 and 857 are provided 45 in the lines 8521 and 854, respectively, to permit control of the speed of swinging of the swinging frame 221.

Closing of the contacts 2371A also energizes a solenoid 858 (FIG. 57). The circuit to the solenoid 858 includes contacts 3022A of the limit switch 3022 (FIG. 10) which are closed when the conveyors 282 and 283 of the first conveyor assembly are at their home position. Energizing of the solenoid 858 advances a valve 859 (FIG. 59) to its alternate position to direct air under pressure from the source 809 through an air pressure line 861 and a line 862 to the cylinders 278 to cause the cylinders 278 to draw piston rods 277 inwardly swinging the plow assemblies to the position 241A of FIG. 10 to bend the major flaps of the carton 50 downwardly to a position to engage the switch actuator 2810 (FIGS. 11 and 12) of the limit switch 2811. Actuation of the switch 2811 causes closing of contacts 2811A (FIG. 57) and 2811B thereof. Closing of the contacts 2811A maintains the solenoid 858 energized. Closing of the contacts 2811B energizes a control relay 864. Energizing of the control relay 864 closes contacts 55 864A and opens contacts 864B thereof. Closing of the

contacts 864A energizes a clutch solenoid 866, which connects the motor 120 to drive the conveyors 282 (FIG. 10) and 283 (FIG. 14) of the first conveyor assembly. Opening of the contacts 864B de-energizes a brake solenoid 867, which releases a brake for the first conveyor assembly. Thus, when the control relay 864 is energized, the first conveyor assembly advances, and when the control relay 864 is de-energized, the first conveyor assembly is stationary. The conveyors of the first conveyor assembly erect the carton to the position shown in FIG. 11 with the plow assemblies restraining trailing minor flaps of the carton but swinging upwardly therewith as already explained. When the carton 71 is square and fully erected, the upper body panel thereof engages the switch operator 301 of the limit switch 302 to close contacts 302A (FIG. 57) and 302B and to open contacts 302C and 302D thereof. Closing of the contacts 302A energizes a solenoid 869 which advances a valve 871 (FIG. 59) to its alternate position to supply air under pressure through a line 872 to cause advance of the piston rods 277 of the cylinders 278 in plow raising direction to raise the plow assemblies to the FIG. 10 full line position to release the carton. A pressure operated pilot valve 8711 (FIG. 59) in the line 872 prevents lowering of the plow assemblies except when there is a positive pressure in the line 862. Opening of the contacts 302C (FIG. 57) prevents energizing of the solenoid 851 so that the swinging frame 221 cannot be tilted to release another carton until the erected carton 71 (FIG. 11) has been advanced from the position shown in FIG. 11.

The carton is advanced from the FIG. 11 position by the conveyors 302 (FIG. 10) and 306 (FIG. 14) of the second conveyor assembly. The second conveyor assembly advances when a control relay 873 (FIG. 57) is energized. When the control relay 873 is energized, contacts 873A close to energize a clutch 874 which connects the second conveyor assembly conveyors 304 and 306 to be driven by the motor 120 and contacts 873B open to de-energize a brake solenoid 876. The brake solenoid 876 operates a brake (not shown) which acts to arrest advance of the second conveyor assembly when the control relay 873 is de-energized. The control relay 873 is energized when a preceding carton at the loading station as indicated at 71B in FIG. 19 is ready to be advanced. The control relay 873 is energized when the switch operator 5742 of the limit switch 5743 is engaged by the bracket 5741 to indicate that the flap closing head of the downstream flap closer is at the dot-dash line position 563A and when the contacts of the limit switch 9017 (FIG. 57) are closed to indicate that the box holding frames 9007 (FIG. 20) are raised. Actuation of the limit switch 5743 closes contacts 5743A (FIG. 57) and opens contacts 5743B (FIG. 56). The contacts 9017 and 5743A (FIG. 57) form a circuit energizing the control relay 873. The conveyors of the second conveyor assembly advance the carton to the loading station 71B (FIG. 19). When the carton reaches the loading station 71B, the flight 3061A (FIG. 14) engages the switch actuator 3062 of the limit switch 3063 opening the contacts thereof as shown in FIG. 57 to de-energize the control relay 873 and stop advance of the second conveyor assembly.

When the carton is advanced by the second conveyor assembly, the control relay 864 is again energized by a circuit through the limit switch contacts 302D and contacts 3022B of the limit switch 3022 (FIG. 10), and

the first conveyor assembly advances until the flight 290 engages the switch actuator 3021 of the limit switch 3022, opening the contacts 3022B (FIG. 57) to de-energize the control relay 864 to stop the first conveyor assembly at its home position.

As the carton approaches the loading station, the limit switch 3572 (FIG. 14) is actuated to close contacts 3572A (FIG. 57) and open contacts 3572B and 3572C (FIG. 56) thereof. Then, the switch actuator 3573 (FIG. 14) of the limit switch 3574 is engaged by the carton to close controls 3574A (FIG. 57), open controls 3574B, and to close controls 3574C (FIG. 56). Closing of the contacts 3572A and 3574A energizes a solenoid 878 which moves a valve 879 (FIG. 58) to its alternate position to supply fluid under pressure through a line 881 to draw the pistons 9013 inwardly of the cylinders 9014 and lower the box holding frames 9007 to the full line position of FIG. 20 to hold the carton at the loading station.

When the carton reaches the loading station, the switch operator 3576 (FIG. 14) of the limit switch 3572 drops off the carton permitting the contacts 3572A (FIG. 57) to open and permitting the contacts 3572B and 3572C (FIG. 56) to close. Closing of the contacts 3574A energizes solenoids 8791 and 8811 (FIG. 57). The solenoid 8791 moves a valve 882 (FIG. 58) to its alternate position to direct fluid under pressure through a line 883 to cause the piston rod 529 of the cylinder 527 to move in a direction to advance the upstream flap closing assembly 516 into the operative position shown in FIG. 29. Energizing of the solenoid 8811 moves a valve 886 (FIG. 58) to the position shown to direct pressure fluid along a line 887 to move the piston rod 366 of the cylinder 363 in a direction to swing the lever member 359 (FIGS. 17 and 18) in flap closing direction.

While the carton is being advanced to the loading station, the stack 401 of articles is advanced from the stack forming machine 403 (FIG. 19) by the pusher assembly 412. The pusher assembly 412 is controlled by a valve 888 (FIG. 58). When the valve 888 is in its alternate position, pressure fluid is directed along a line 889 to the cylinder 416 and the piston rod 414 is drawn inwardly of the cylinder 416 to retract the pusher bars 4161 (FIG. 19). When the valve 888 (FIG. 58) is moved to the position shown, pressure fluid is directed along a line 890 and the piston rod 414 is moved outwardly to advance the stack onto the stack supporting plate 449 (FIG. 34) and the stack supporting brackets 451 and 452 (FIG. 36). A solenoid 891 (FIG. 58) advances the valve 888 to the position shown. A solenoid 8921 advances the valve 888 to its alternate position. The solenoid 891 (FIG. 56) is energized by a circuit including the contacts of the limit switch 5132 (FIG. 35), which indicates that the head 513 is retracted, contacts 5141A (FIG. 56) of the limit switch 5141 (FIG. 35) which indicates that the stack advancing assembly 402 is upright, and contacts 892A (FIG. 56) of a control relay 892. The control relay 892 is energized when the limit switch 5106 (FIG. 38) is closed to indicate a stack is compressed against the stack gripping portion of the bracket 473 and associated members. In addition, the circuit which energizes the solenoid 891 includes switch contacts 893 associated with the stack forming machine, which will not be described in detail. The control relay 892 includes contacts 892B which can energize the solenoid 8921 to cause retraction of the

pusher assembly 412 (FIG. 19). The circuit to the solenoid 8921 (FIG. 56) also includes switch contacts 894 associated with the stack forming machine, which will not be described in detail. The control relay 892 additionally includes contacts 892C, 892D and 892E (FIG. 57).

When the pusher assembly 412 has been fully extended, the switch 4172 (FIG. 19) is actuated to open contacts 4172A (FIG. 56) and 4172B and to close contacts 4172C. Closing of the contacts 4172C energizes a solenoid 896. The solenoid 896 advances a valve 897 (FIG. 58) to the right to direct fluid through a line 898 to the cylinder 488 to cause extension of the piston rod 484 to raise the head 513 (FIGS. 33 and 34). The head 513 is raised until the stack engages the cam 5101 (FIG. 38) to indicate that the stack is compressed against the projecting portions of the bracket 473 and associated members and to actuate the switch 5106 energizing the control relay 892 (FIG. 56) to open the switch contacts 892D thereof de-energizing the solenoid 896. A pilot check valve 899 (FIG. 58) in the line 898 prevents retraction of the piston rod 484 except when there is a positive pressure in a return line 901.

When the switch 5106 (FIG. 56) closes indicating that the stack is compressed and the switch contacts 3572C are closed indicating that a carton is at the loading station, a solenoid 903 is energized. The solenoid 903 moves a valve 904 (FIG. 58) to the position shown at which fluid under pressure is introduced through a line 906 to the cylinder 5131 to cause the piston rod 513R to be extended to cause the stack advancing assembly 402 to swing to the dot-dash line position of FIG. 35. A pilot check valve 907 (FIG. 58) in the line 906 prevents return swinging of the assembly 402 until there is a positive pressure in a return line 908.

Closing of the contacts 892E (FIG. 57) of the control relay 892 energizes a solenoid 909. The solenoid 909 advances a valve 911 (FIG. 58) to the position shown at which fluid is directed along a line 912 to the rotary motor 378 (FIG. 22) to cause extension of the stack supporting tongue to the dot-dash line position 369A of FIG. 23 in position to engage flat articles of the stack as the stack is inserted into the carton 71.

When the stack advancing assembly 402 is fully tilted to the dot-dash line position of FIG. 35, the limit switch 5136 is actuated to close contacts 5136A (FIG. 56) and 5136B (FIG. 57). Closing of the contacts 5136A (FIG. 56) energizes the solenoid 896 and a solenoid 914. Energizing of the solenoid 896 causes further advance of the head 513 (FIG. 35) to push the stack into the carton 71. Energizing of the solenoid 914 causes advance of a valve 916 (FIG. 58) to its alternate position at which pressure fluid in a line 917 advances the piston rods 458 and 474 inwardly of the cylinders 461 and 477 causing swinging of the cranks 457 and 472 (FIG. 34) in a direction to cause the cranks 457 and 472 and associated members to release the stack so that the stack can be advanced into the carton 71. Closing of the contacts 5136B (FIG. 57) energizes a solenoid 918 which moves the valve 911 (FIG. 58) to its alternate position to direct pressure fluid along a line 919 to drive the motor 378 in a direction to retract the tongue 369 (FIGS. 19 and 23) as the stack is inserted into the carton 71.

When the head 513 has been fully advanced to insert the entire stack into the carton 71, the limit switch

5140 (FIG. 35) is actuated to close the contacts thereof to energize solenoids 922 and 923 (FIG. 57). The solenoid 922 moves a valve 924 to the position shown in FIG. 58 at which pressure fluid is directed along a line 926 into the cylinders 539 and 571 to extend piston rods 543 and 568 thereof to close the flap closing heads 538 (FIG. 29) and 563 (FIG. 19) to close minor rear flaps of the carton 71. Energizing of the solenoid 923 moves the valve 879 to the position shown to direct pressure fluid along a line 928 to the cylinders 9014 to extend the piston rods 9013 thereof to raise the box holding frames 9007 (FIG. 20). When the box holding frames 9007 are raised, the limit switch 9017 is actuated to close the contacts thereof as shown in FIG. 57.

When the downstream flap closing head 563 is closed as shown in FIG. 19, the limit switch 5761 is actuated to close contacts 5761A (FIG. 56) and 5761B (FIG. 57). When the upstream flap closing head 538 (FIG. 29) is closed, the contacts of the limit switch 5514 (FIG. 30) are closed as shown in FIG. 56. Closing of the contacts 5761B energizes a solenoid 931 which advances a valve 932 (FIG. 58) to the position shown to direct pressure fluid along a line 933 to the cylinder 562 to extend the piston rod 559 to advance the downstream flap closing head to the dot-dash line position 563A of FIG. 19. When the head is at the position 563A, the limit switch contacts 5743A (FIG. 57) are closed to energize the control relay 873 to advance the second conveyor assembly as already explained. Closing of the contacts 5761A (FIG. 56) energizes a control relay 935 which closes contacts 935A and 935B and opens contacts 935C and 935D. Closing of the contacts 5761A also energizes a solenoid 936 which advances the valve 897 (FIG. 58) to the left to direct fluid through the line 901 to the cylinder 488 and cause retraction of the head 513 (FIGS. 33 and 34). As the head 513 is being withdrawn, the switch actuator 514L (FIG. 35) of the limit switch 5142 is engaged to close the contacts thereof (FIG. 56) to energize a solenoid 938. The solenoid 938 moves the valve 904 (FIG. 58) to its alternate position to direct fluid along the line 908 to retract the piston rod 513R and restore the stack advancing assembly 402 to upright position (FIG. 35). When the switch contacts 5142 (FIG. 56) close, a control relay 1000 is energized to close contacts 1000A, to open contacts 1000B and to close contacts 1000C. Closing of the contacts 1000C energizes a solenoid 1001 which moves the valve 916 (FIG. 58) to the position shown at which fluid is directed along a line 1002 to the cylinders 461 and 477 to extend the piston rods 458 and 474 and swing the cranks 457 and 472 (FIG. 34) to stack gripping position. A pilot check valve 1003 (FIG. 58) in the line 1002 prevents inward movement of the piston rods 458 and 474 except when there is a positive measure in the line 917.

When the stack advancing assembly 402 reaches upright position, the limit switch 5141 (FIG. 35) is actuated to close the contacts 5141A (FIG. 56) and open contacts 5141B thereof. Closing of the contacts 5141A makes it possible for the solenoid 891 to be energized to advance the pusher assembly 412 (FIG. 19). Opening of the contacts 5141B prevents energizing of the solenoid 914 to release the stack holders when the stack advancing assembly 402 is upright.

When the head 513 (FIG. 35) has been completely retracted, the limit switch 5132 is actuated to close the

contacts thereof (FIG. 56), which also serves to make possible the energizing of the solenoid 891 to advance the pusher assembly 412 (FIG. 19).

The carton is now advanced through the glue assemblies 599 (FIG. 44). When the leading edge of the carton engages the actuator 647 of the limit switch 652, contacts 652A (FIG. 57) open and contacts 652B close. Closing of the contacts 652B energizes solenoids 941, 942, 943 and 944, a time delay relay 946, and a glue solenoid 947. Energizing of the solenoid 947 moves a valve 948 (FIG. 59) to its alternate position to direct air under pressure to the glue valves 628 to move the glue valves to their alternate positions. When the glue valves are in their alternate positions, glue from a reservoir 954 is pumped by a pump 956 through a line 957 to the glue heads 631 and 632 to apply glue to the major flaps of the carton. The glue pump 956 is powered by an appropriate pneumatically driven motor 959. The solenoid 941 (FIG. 58) moves the valve 932 to its alternate position to direct fluid through a line 961 to power the cylinder 562 for retracting the downstream head 563 (FIG. 19). The solenoid 942 (FIG. 58) moves the valve 882 to the position shown to supply fluid through a line 963 to the cylinder 527 for withdrawing the upstream flap closing assembly (FIG. 29). The solenoid 943 moves the valve 924 (FIG. 58) to its alternate position to direct fluid through a line 964 to the cylinders 539 and 571 to cause opening of the flap closing heads 538 (FIG. 29) and 563 (FIG. 19). The solenoid 944 moves the valve 886 (FIG. 58) to its alternate position to direct fluid along a line 966 to the cylinder 363 to withdraw the flap closing assembly 358 (FIG. 18). Energizing of the time delay relay 946 (FIG. 57) opens time delay contacts 946A to de-energize the glue solenoid 947 after a sufficient time delay to permit applying of glue in the usual fashion so that, in case there is a machine failure or jam, glue is only delivered for a limited time. Energizing of the time delay relay 946 also closes instantaneous contacts 946B and opens instantaneous contacts 946C.

When the carton has been advanced to the position at which the first glue pattern is completed, the switch actuator 648 (FIG. 44) of the limit switch 653 is engaged by the leading edge of the carton to open the contacts thereof (FIG. 57) to de-energize the glue solenoid 947. At this time, the actuators of the limit switches 654 and 656 (FIG. 44) are engaged by the carton and the contacts of the limit switch 656 (FIG. 57) are closed and the contacts of the limit switch 654 are open. When the carton reaches the point for the start of the second glue pattern, the switch operator of the switch 654 falls from the carton to close the contacts thereof (FIG. 57) energizing the glue solenoid 947. When the end of the second glue pattern is reached, the switch actuator of the limit switch 656 falls from the carton opening the contacts of the limit switch 656 to de-energize the glue solenoid 947.

Closing of the contacts 946B of the time delay relay 946 energizes a clutch solenoid 967 which connects the conveyors 701 (FIG. 1) and 702 (FIG. 53) of the third conveyor assembly to the motor 120 to be driven thereby and to advance the carton from the glue assemblies 599 (FIG. 1) to the compression section 713. When the carton reaches a switch actuator 968 (FIG. 54) of a limit switch 969, limit switch contacts 969A (FIG. 56) open and limit switch contacts 969B (FIG. 57) close to energize a control relay 971 to open

contacts 971A (FIG. 56), to close contacts 971B (FIG. 57) and 971C and to open contacts 971D. Closing of the contacts 971B energizes a brake solenoid 972 which arrests the third conveyor assembly when the carton reaches the vertical compression section. Closing of the contacts 971C energizes a clutch solenoid 973 to connect the vertical conveyors 736 and 751 to the motor 120 to be driven thereby. Opening of the contacts 971D de-energizes a brake solenoid 9731 of the vertical conveyor assembly and de-energizes the clutch 967 of the third conveyor assembly. A mechanical stop (not shown) can be associated with the limit switch 969 (FIG. 54) for positively arresting advance of the carton in the compression section. The vertical conveyor assembly moves the carton upwardly, and the carton comes free of the actuator 968 of the limit switch 969 to permit the contacts 969B thereof (FIG. 57) to open de-energizing the control relay 971. The carton is advanced upwardly until the next succeeding flight 749 (FIG. 53) of the vertical conveyor assembly engages the switch operator 743 of the limit switch 744 to open contacts 744A (FIG. 57) and close contacts 744B. Opening of the contacts 744A de-energizes the clutch solenoid 973 to permit the vertical conveyor assembly to stop. Closing of the contacts 744B energizes the brake solenoid 9731 which arrests the vertical conveyor assembly.

When the control relay 971 is de-energized, the contacts 971D energize the clutch 967 to drive the third conveyor assembly until the flight 709A (FIG. 1) engages the switch actuator 711 of the limit switch 712 to close contacts 712A (FIG. 57) energizing the brake solenoid 972 of the third conveyor assembly and opening contacts 712B to de-energize the clutch solenoid 967 of the third conveyor assembly so that the third conveyor assembly stops at its home position.

The carton is advanced upwardly step-by-step until it engages the switch actuator 781 (FIG. 53) of the limit switch 782 opening contacts 782A (FIG. 56) and closing contacts 782B (FIG. 57). Closing of the contacts 782B energizes a solenoid 976 which moves a valve 977 (FIG. 58) to the position shown to direct fluid along a line 978 to the cylinder 793 to move the piston rod 794 outwardly of the cylinder 793 to swing the swinging bar 796 to the left as shown in FIG. 54 to advance the carriage 786 to the left to discharge the carton onto the conveyor 783. When the carton has been ejected, the swinging bar 796 engages the switch operator 802 of the limit switch 800 to open contacts 800A (FIG. 57) and to close contacts 800B. Closing of the contacts 800B energizes a solenoid 979 which moves the valve 977 (FIG. 58) to its alternate position to direct fluid along a line 980 to cause retraction of the piston rod 794. When the piston rod 794 has been fully retracted, the swinging bar 796 (FIG. 54) engages the switch actuator 803 of the limit switch 801 to close the contacts thereof (FIG. 57).

If it is necessary to advance a carton out of the vertical compression section without waiting for a full set of cartons passing therethrough, a push button switch 982 (FIG. 57) can be moved to its alternate position to close contacts 982A energizing the clutch solenoid 973 of the compressor conveyor assembly and opening contacts 982B to de-energize the brake solenoid 9731 of the compressor conveyor assembly.

If, through a malfunction of the machine, two cartons are advanced onto a single level of the vertical con-

veyor assembly, the second carton engages a switch actuator 984 (FIG. 54) of a limit switch 986 as the vertical conveyor assembly moves the cartons upwardly to open the contacts thereof as shown in FIG. 56 to de-energize the control relay 813 to stop operation of the machine. If the control relay contacts 971A and the contacts 5743B are both opened at the same time to indicate a carton is at the lower level of the vertical compression section engaging the actuator 968 (FIG. 54) of the limit switch 969 and a second carton is at the loading station, the control relay 813 (FIG. 56) is similarly de-energized to stop the machine. The control relay 813 is also de-energized to stop the machine if the limit switch contacts 969A and 782A are both open concurrently indicating a carton at the lower level of the compression section when another carton is at the upper level of the compression section.

The pusher assembly 412 can be retracted by moving a push button switch 988 to its other position (FIG. 56) to close contacts 988A energizing the solenoid 8921 and opening contacts 988B to de-energize the solenoid 891. Contacts 988C are closed to energize the solenoid 1001 to advance the stack holding cranks 457 and 476 (FIG. 34) and associated members to stack holding position.

The stack advancing assembly 402 (FIG. 35) can be advanced to upright position by moving a switch 991 (FIG. 56) to its other position to close contacts 991A and 991B and to open contacts 991C. Closing of the contacts 991A energizes the solenoid 938 which causes swinging of the stack advancing assembly 402 to upright position.

The machine for erecting and loading cartons which has been illustrated in the drawings and described above is subject to structural modification without departing from the spirit and scope of the appended claims.

Having described our invention, what we claim as new and desire to secure by letters patent is:

1. A machine for loading a stack of articles in a carton which comprises a pivotally mounted stack turning frame, stack guiding means extending outwardly of the axis of the stack turning frame, means for advancing the stack in upright position into the stack turning frame adjacent the stack guiding means when the stack guiding means is upright, a stack advancing head mounted on the stack turning frame and engageable with the underside of the stack, stack holding flap means mounted on the stack guiding means remote from the axis of the stack turning frame, means for advancing the head toward the flap means to hold the stack against the flap means, means for swinging the stack turning frame from the position in which the stack guiding means is upright to a position in which the stack guiding means is horizontal, tracks opposite the stack turning frame, means for advancing an erect carton along the tracks to a loading station at which the interior of the carton is aligned with the stack guiding means in horizontal position, means for withdrawing the flap means from the stack and for further advancing the head to advance the stack into the carton, and means for closing flaps of the carton to hold the stack in the carton.

2. A machine as in claim 1 wherein the means for advancing the head includes a first crank pivotally mounted on the stack turning frame, a first link supported at one end at a free end of the first crank, a sec-

ond link connecting the other end of the first link to a point on the stack turning frame spaced from the axis of the first crank to form a first parallelogram linkage, a second crank pivotally mounted on one of the pivots of the first link, a third link pivotally mounted on the other of the pivots of the first link, a support rod connecting free ends of the second crank and the third link to form a second parallelogram linkage, the head being carried by the support rod, means interconnecting the cranks to cause the second crank to swing through an angle twice as great as the angle through which the first crank swings so that the head advances along a substantially straight line as the cranks swing, and means for swinging the first crank between a first position in which the head underlies the stack and a second position in which the head is advanced to advance the stack into the carton.

3. A machine as in claim 2 wherein the second crank is mounted on the pivot of the first link which is supported by the first crank.

4. A machine as in claim 3 wherein the means interconnecting the cranks includes a sprocket mounted on the second crank at the pivot thereof with the first link, a stationary sprocket mounted on the stack turning frame at the axis of the first crank, and chain means interconnecting the sprockets, the pitch diameter of the stationary sprocket being twice that of the other sprocket.

5. A machine as in claim 1 wherein a tongue supporting means is mounted at the loading station at the side of the tracks remote from the stack turning frame, a tongue is mounted on the tongue supporting means, and means is provided on the tongue supporting means for extending the tongue into the carton when the carton is at the loading station to support the stack as the stack is advanced into the carton to support articles in the stack as the stack starts to enter the carton and for withdrawing the tongue as the stack is advanced further into the carton.

6. A machine as in claim 1 wherein the means for advancing the carton to the loading station includes conveyor means, flight means mounted on the conveyor means and engaging a trailing side of the carton to advance the carton, carton holding means pivotally mounted at the loading station and engageable with a leading side of the carton at the loading station to hold the carton against the flight means, means for swinging the carton holding means into engagement with the carton when the carton is at the loading station and while the stack is loaded into the carton and for swinging the carton holding means out of the path of the carton when the carton has been loaded, the carton advancing means advancing the loaded carton from the loading station when the carton holding means has been swung out of the path of the carton.

7. A machine as in claim 1 wherein the means for closing flaps of the carton includes an upstream flap closing frame, an upstream flap closing head pivotally mounted on the upstream flap closing frame, means for moving the upstream flap closing frame between a retracted position free of the path of a carton being advanced to the loading station and an advanced position in which the upstream flap closing head is in position for closing an upstream flap of the carton at the loading station, a downstream flap closing frame, a downstream flap closing head pivotally mounted on the downstream flap closing frame, means for moving the downstream

flap closing frame between a retracted position in which the downstream flap closing head is in position for closing a downstream flap of the carton at the loading station and an advanced position, means for swinging the flap closing heads to close the upstream and downstream flaps of the carton when the stack has been advanced into the carton, free ends of the flap closing heads being spaced sufficiently to permit removal of the stack advancing head therebetween, and means for moving the downstream flap closing frame to the advanced position in which the downstream flap closing head is adjacent the upstream flap closing head when the stack advancing head has been removed so that the downstream flap closing head holds the upstream carton flap in closed position as the carton is advanced from the loading station.

8. A machine as in claim 1 wherein the means for advancing the carton to the loading station includes a conveyor having flights engageable with the carton to advance the carton along the tracks from a carton erecting station to the carton loading station, means for delivering a collapsed carton onto the tracks with flaps of the carton extending outwardly of the tracks at the carton erecting station, a carton erecting plow assembly including a first lever pivotally mounted above the carton erecting station, a second lever pivotally mounted above the carton erecting station, a link connecting free end portions of the levers, a carton erecting head mounted on the link, means for swinging the levers downwardly to bring the head against one of the major flaps of the carton to fold that one of the major flaps, one of the minor flaps and the other major flap downwardly, there being a slot in the carton erecting head which extends horizontally and receives the other minor flap when the plow assembly is in a lowered position, means for advancing the carton along the track while the other minor flap is restrained by the carton erecting head, the levers and the link swinging upwardly as the carton is advanced along the tracks with the head and the link swinging from the position in which the slot in the head is horizontal to a position in which the slot is upright as the levers swing upwardly to a carton erected position to erect the carton, and means for swinging the levers upwardly further to cause

the head to release the other minor flap of the carton, the carton advancing means advancing the carton from the carton erecting station to the loading station in erect position.

- 5 9. In a machine for loading articles into a rectangular carton having a pair of major flaps and a pair of minor flaps at one end, a carton erecting device which comprises track means, means for delivering a collapsed carton onto the track means with flaps thereof extending outwardly of the track means at a carton erecting station, a carton erecting plow assembly including a first lever pivotally mounted above the carton erecting station, a second lever pivotally mounted above the carton erecting station, a link connecting free end portions of the levers, a carton erecting head mounted on the link, means for swinging the levers downwardly to bring the head against one of the major flaps of the carton to fold that one of the major flaps, one of the minor flaps and the other major flap downwardly, there being a slot in the carton erecting head extending horizontally and which receives the other minor flap when the plow assembly is in a lowered position, means for advancing the carton along the track while the other minor flap is restrained by the carton erecting head, the levers and the link swinging upwardly as the carton is advanced along the track means with the head and the link swinging from the position in which the slot is horizontal to a position in which the slot is upright as the levers swing upwardly to a carton erected position to erect the carton, and means for swinging the levers upwardly further to cause the head to release the other minor flap of the carton, the carton advancing means advancing the carton from the carton erecting station in erect position.
